UNITED STATES PATENT OFFICE.

WILLIAM H. COOK, OF TOLEDO, OHIO.

DETONATING ALARM.

1,398,362.

Specification of Letters Patent. Patented Nov. 29, 1921.

Application filed January 6, 1921. Serial No. 435,362.

To all whom it may concern:

Be it known that I, WILLIAM H. COOK, a citizen of the United States of America, residing at Toledo, Lucas county, Ohio, have 5 invented new and useful Detonating Alarms, of which the following is a specification.

This invention relates to detonating alarms.

This invention has utility when incorporated in protective or burglar alarms for windows, doors, etc.

Referring to the drawings:

Figure 1 is a perspective view, with parts broken away, showing an embodiment of the 5 device mounted in position as to a door;

Fig. 2 is a side elevation of the device of Fig. 1 showing the device or alarm in set position, carried by a bracket secured to a sash, so that the window may be open for 20 ventilation, but further opening will cause the alarm to be tripped;

Fig. 3 is a view of the device with the detonator holder in section, showing the device in tripped position and mounted on the 25 cross sash of a two part window;

Fig. 4 is a perspective view of the base;

Fig. 5 is a view on the line V—V in Fig. 2 looking in the direction of the arrow and having the detonator carrier shown in dotted 30 lines;

Fig. 6 is a perspective view of the bracket, which is shown carrying the device in Fig. 2; and

Fig. 7 is a perspective view of the control 35 arm of the device.

A door 1 is shown mounted so as to swing into opening or frame 2 which carries screws 3, 4, with their heads slightly clear of the frame 2. For the screw 3 is provided end 40 notch 5 and for the screw 4, a side notch 6 in base member 7 of the alarm device. A portion 8 of the alarm device is somewhat raised from the base 7 and has ears 9, 10, on the outer side inwardly extending to embrace 45 the broad end of a spring member 11 shown as a flat or leaf spring with a widened rear end 12 which may be further anchored by rivet 13 to the raised portion 8 of the base member 7. The narrow or free end of the 50 spring member or mounting 11 has therein an opening 14 through which protrudes a cylindrical member or holder 15 having a base flange 16 which may seat up against the underside of the member 11 when the 55 holder 15 is in position. This holder 15, 16, may be frictionally locked or riveted to the

spring member 11. Concentrically with this holder 15 is cylindrical opening 17 therethrough having at its lower portion a peripheral annular countersunk portion 18.

Rising from the base member 7 below this holder 15 is an upwardly extending impact receiver 19 having a central or intermediate point 20 as the rim fire coacting means for a blank cartridge in the opening 17 of the 65 holder 15.

Upstanding from the base member 7, adjacent the impact receiver 19, 20, is arm 21, having in its lower portion a pivot bearing providing rivet 22 for a trigger member having a trigger ledge 23 and a tapered extension 24 therebeyond. This trigger member 23, 24, pivotally mounted on the bearing 22 is carried adjacent upstanding portion 21 of the base member 7 and the ledge 23 coacts 75 with the under side of the holder 15 against the resistance of the spring 11, thus holding the device in a set position with a blank cartridge 25 in the seat 17, 18, held away from the impact receiver 19, 20.

Upstanding member 21 of the base 7 has near its top a second pivot bearing 26 carrying a member having an upward channel portion 27 engaged on one side by the upward projection 24 of the trigger 23, 24. 85 This channel portion 27 is part of a control member pivoted on the bearing 26 and having control extension or handle 28.

The trigger bearing rivet 22 has on the opposite side of the member 21 an annular 90 flange or head 29 about which may be partially wrapped a U-shaped spring having one leg 30 engaging the channel position 27 oppositely from the extension 24. The other leg 31 of this U-shaped spring 30, 31, enters 95 opening 32 in the extension 24 of the trigger member 23, 24, to hold the trigger thrown toward the holder 15, 16. Accordingly the spring 30, 31, not only normally throws the trigger 23 out into position to hold the lifted 100 member or holder 11, 15, away from the impact receiver 19, 20, but also simultaneously holds the control member 27, 28, so rocked that the portion 28 is outward or away from the upstanding portion 21.

In practice this device is one which may readily be installed or demounted by merely slipping the notches into position over projecting screw heads or other points for holding the device in position where it is desired 110 to have the detonating alarm placed as in the instance of mounting on the door frame

2, or upon window sash 33. While the mounting or spring member 11 is quite rigid for a positive throwing of the detonator against the impact receiver, such may be 5 lifted into raised position or set by a screw driver or other tool drawn upward in the region of the seat 15 to pull it up into such a position that the spring 30, 31, will throw the trigger portion 23 out to hold the member so elevated. When thus normally set the 10 control member has its arm 28 swung outward or away from the member or base 7. In the event the one who sets the alarm desires to leave by the opening at which the 15 alarm is set, this may occur, for the control member 28 may be swung toward the alarm device by a closing of an opening by a door or window without setting off the alarm. At once the part has passed the control member 20 28, it is again thrown outward by the spring member 30, 31. However, should the closure for this opening be moved in the reverse direction or against the underside of the control member 28, such movement will 25 cause the channel portion 27 to act upon the extension 24 of the trigger member 23, 24, to draw the ledge 23 away from holding position as to the mounting member 11 and the holder 15 so that the spring 11 at once 30 swings the cartridge 25 in the holder 15 against the impact receiver 19, 20, and for rim fire this projection 20 will set off the percussion and the detonating discharge will result.

35 The device is conveniently mounted in any desired position as to the opening and may even be mounted in a position which would leave the seat downwardly open. In such last mentioned instances, to keep the cartridge 25 in the holder 15 from vibrating or shaking out, the cartridge 25 may be at its open end slightly squeezed or distorted so that it will frictionally engage in the seat 17 of the holder 15, 16. The device may be 40 charged in its set position or may be conveniently removed by slipping it out of its notches and taking it down at such times as may be desired. Further if it is desired to leave the device in position all that is necessary to do is to throw the control member arm 28 into parallel relation with the up-standing arm portion 21 at which position the channel 27 rides to bring the spring arm 30 into seat 34 and the device is held inoperative and the trigger 23 is still protruding and maintains the device set, but it is set not in a position to be thrown off by the control member for the control member is clear of the relative movement to effect 45 the shifting of the control member, except by manually pulling outward of this member 28.

50 When it is desired to use this device in connection with a window against further window disturbance, but with the window

open for ventilation, instead of mounting the device directly, it may be carried by a bracket 35 mounted by screws 36 on window stop 37 at the desired location for the member 28 to project into the path of travel of 70 the sash 33. Lugs 38, 39, permit detachable mounting of the device to the bracket 35.

A detonating alarm of this disclosure is a substantial compact device of insured operation as to all of its mechanisms. It may 75 not be distorted or readily disturbed when in operative position except as designed in its construction for such disturbances. As it is made throughout of wrought metal parts, it is of the most substantial character. 80 The sheet metal base, trigger and control member are parts which are readily and economically stamped out and the spring portion is also a substantial part not only operating as a spring but also as a mounting for 85 the holder. The holder is a tubular member which is readily formed to provide a seat as herein disclosed. The parts are such as might easily be produced in quantity and as so produced may be assembled into the 90 devices of standard form with interchangeable parts for use in such diverse places as may be desired by the householder or for use in or about a place of business. While the device is shown as a cartridge carrying 95 alarm of the detonating type and it is peculiarly designed for such utility, still the detonating features may be varied as found convenient in practice or to fit the conditions in which it is desired to be used. In those 100 instances where it is desired to mount the device some distance from the object, movement of which object is to set off the alarm device, in eye 40 may be engaged a wire or rod 41 extending to such object.

105 What is claimed and it is desired to secure by Letters Patent is:

1. A detonating alarm embodying a holder for a detonator, a mounting for the holder including a flat spring, a base for the mounting including an impact receiver against which the holder may throw a detonator, and a trigger carried from the base to engage and hold the holder against spring action, said holder being carried and anchored 110 by the flat spring against movement other than directly to strike the impact receiver when released by the trigger.

2. A detonating alarm embodying a base, a swingable detonator carrier holder providing a seat for a cartridge, a trigger carried by the base for holding the cartridge in set position with the holder extending away from the base and an impact receiver opposing the seat, said seat having an annular 125 counter-sink on the end toward the receiver for the flange of a cartridge to shield the seat from the impact receiver.

3. A detonating alarm embodying a base, a swingable detonator carrier holder, extend- 130

- ing in set position away from said base, and a retractile trigger mounted on said base and coacting in set position for holding the holder away from the receiver.
- 5 4. A detonating alarm embodying a holder, an impact receiver, a mounting restricting holder travel in a single plane toward and from the receiver, a trigger for holding the holder away from the receiver,
- 10 a relatively movable control member for shifting the trigger to a position away from the holder, and a support adjacent the receiver for the trigger and control member.
5. A detonating alarm embodying a holder, an impact receiver, a mounting restricting holder travel in a single plane toward and from the receiver, a trigger for holding the holder away from the receiver, a relatively movable control member for
- 20 shifting the trigger to a position away from the holder, means engaging the trigger to shift it into a position to intercept holder travel, and a support adjacent the receiver for the trigger, member and means.
- 25 6. A detonating alarm embodying a holder, an impact receiver, a mounting restricting holder travel in a single plane toward and from the receiver, a trigger for holding the holder away from the receiver,
- 30 a control member for shifting the trigger away from the holder, a spring normally holding the control member in position away from the trigger, and a support adjacent the receiver for the trigger, member and
- 35 spring.
7. A detonating alarm embodying a holder, an impact receiver, a mounting restricting holder travel in a single plane toward and from the receiver, a trigger for holding the holder away from the receiver, 40 a control member for shifting the trigger away from the holder, a single spring normally holding the trigger in set position and the member away from the trigger shifting position, and a support adjacent the receiver 45 for the trigger, member and spring.
8. A detonating alarm embodying an impact receiver, a detonating carrier, a flat spring between the receiver and carrier, said flat portion of the spring being transverse 50 of the travel of the carrier toward the receiver, a base for the receiver and carrier, and a trigger carried from the base for holding the carrier away from the receiver.
9. A detonating alarm embodying a tubular holder for a cartridge, a base having an impact receiver, a flat spring anchored at a plurality of points to the base and having at its free end an opening for receiving the holder, and a trigger carried by the base 60 for holding the holder away from the receiver.
10. A detonating alarm embodying a base provided with notches to permit detachable mounting of the alarm, and anchoring projections as to which the base may be shifted 65 to bring its notches into alarm holding position.
11. A detonating alarm and a supporting bracket provided with means for detachably carrying the bracket, and fixed anchoring means as to which the bracket may be shifted to bring the means into alarm mounting position in a set position to extend away from the base.

In witness whereof I affix my signature.

WILLIAM H. COOK.

It is hereby certified that in Letters Patent No. 1,398,362, granted November 29, 1921, upon the application of William H. Cook, of Toledo, Ohio, for an improvement in "Detonating Alarms," errors appear in the printed specification requiring correction as follows: Page 3, claim 9, line 62, after the syllable "ceiver" and before the period insert the words *in a set position to extend away from the base*; same page, claim 11, lines 74 and 75, strike out the words "in a set position to extend away from the base;" and that the said Letters Patent should be read with these corrections therein that the same may conform to the record of the case in the Patent Office.

Signed and sealed this 3d day of January, A. D., 1922.

[SEAL.]

WM. A. KINNAN,
Acting Commissioner of Patents.
